UNITED STATES PATENT OFFICE.

ALFRED WEILAND, OF PHILADELPHIA, PENNSYLVANIA.

CARBURETER FOR INTERNAL-COMBUSTION ENGINES.

1,276,841.

Specification of Letters Patent. Patented Aug. 27, 1918.

Application filed March 6, 1917. Serial No. 152,528.

To all whom it may concern:

Be it known that I, ALFRED WEILAND, a citizen of the United States, residing at Philadelphia, in the county of Philadelphia and State of Pennsylvania, have invented a certain new and useful Improvement in Carbureters for Internal-Combustion Engines, of which the following is a specification.

The present invention relates generally to 10 a carbureter for internal combustion engines and more specifically to the control, regulation and mixing of the liquid fuel and air as discharged to the motor intake.

It is an object of the invention to provide 15 means under the control of pressure conditions in the motor intake for definitely proportioning the liquid fuel and air so that irrespective of running conditions the motor receives a proper and efficient mixture 20 for the required condition. It is an object therefore to provide means for automatically supplying a mixture rich in liquid fuel under starting or slow speed conditions and which mixture can be automatically varied 25 or controlled in such a manner that under high speed conditions, for example, or conditions of relatively light load, the liquid fuel will be automatically starved, or cut down while the quantity of air in the mixture 30 is proportionately increased.

A further object of the invention is to provide a carbureter having a main liquid fuel reservoir which automatically refills 35 from time to time from an auxiliary reservoir and this latter reservoir being subjected to pressure conditions existing in the motor intake and adapted to replenish itself automatically while the main reservoir is feeding the motor.

40 It is a further object of the invention to provide an auxiliary reservoir for replenishing the main fuel reservoir and subjecting said auxiliary reservoir to vacuum conditions which are maintained substantially 45 constant irrespective of the position of the throttle valve or variations in the pressure conditions in the motor intake while the motor is in operation.

For the purpose of illustrating my invention, I have shown in the accompanying drawings one form thereof which is at present preferred by me since the same has been found in practice to give satisfactory and reliable results, although it is to be understood 50 that the various instrumentalities of which my invention consists can be variously

arranged and organized and that my invention is not limited to the precise arrangements and organization of the instrumentalities as herein shown and described. 60

Referring to the drawings:

Figure 1 represents a plan of a carbureter embodying my invention.

Fig. 2 represents a section on line 2—2 of Fig. 1. 65

Fig. 3 represents a section on line 3—3 of Fig. 2.

Fig. 4 represents a plan of a modified form of the invention.

Fig. 5 represents a section on line 5—5 of Fig. 4. 70

Fig. 6 represents a section on line 6—6 of Fig. 4.

Fig. 7 represents a section on line 7—7 of Fig. 5. 75

Fig. 8 represents a section on line 8—8 of Fig. 5.

Fig. 9 represents a plan of another modification of the invention.

Fig. 10 represents a section on line 10—10 of Fig. 9. 80

Fig. 11 represents a section on line 11—11 of Fig. 9.

Fig. 12 represents a section on line 12—12 of Fig. 9. 85

1 designates the casing of the carbureter which is provided with a removable cover or top 2 by means of which access is had to the interior of the carbureter for purposes of repair or otherwise, as will be understood. In the present instance, the casing 1 is so constructed as to form a carbureting chamber 3 a main fuel reservoir 4, a supplemental or storing reservoir 5 and an auxiliary reservoir 6, the latter having direct connection and communication with a source of low level liquid supply (not shown) by way of the pipe 7. The carbureting chamber 3 communicates with the atmosphere through the main air inlet passage 8 and discharges into the motor intake by way of the outlet 9 and this outlet portion is of course subject to the pressure conditions existing in the aforesaid motor intake. 90

As here shown the carbureter nozzle or the mixture jet is formed in a part of the throttle valve controlling means and is located substantially transversely of the chamber 3 so that when the throttle is open, 100 the air entering by way of the passage 8 and traversing the chamber 3 is divided and 105

110

passes to opposite sides of the nozzle structure. Referring to Fig. 2, 10 designates the throttle valve which is suitably shaped and located to cut off the carbureting chamber 3 from the motor intake as desired and in the present instance this valve is formed with a central sleeve 11 which is fixed to the tubular stem 12 of the throttle valve operating means. Thus the stem 12 has a bearing 5 in the carbureter casing 1 and terminates in an enlarged head 13 which seats upon the casing top and carries the throttle operating lever 14 by which the parts are moved as required. As here shown the head 13 forms a chamber 15 the otherwise open end of which is closed by a cap 16 provided with a plurality of air inlet openings 17 for a purpose presently to be described. The stem 12 is further provided with an intermediate body 20 portion 18 which serves as a guide-bearing for the tubular plunger 19 and also provides the circumferential extension 20 which is arranged concentrically of the plunger 19 and terminates at a point substantially below the normal liquid fuel level. In this connection, it will be noted that a plurality of openings 21 are provided in the said extension at substantially the normal level line of the liquid fuel in main fuel reservoir 4 and serve to permit air to escape from the interior of said extension and carry liquid fuel to the jet outlets 22. These outlets 22 are formed respectively at opposite sides of the throttle valve 10 and communicate with the space 23 between the extension 20 and the sleeve plug 24 which is threaded into the casing 1 in alinement with the stem 12 and in fact is adapted to telescope with the end portion of this stem to form the aforesaid space 23. The body portion of the plug 24 forms a jet reservoir 25 which is supplied with fuel from the main reservoir 4 by way of the passage 26 which has communication with the inlet 27 in the plug 24.

28 designates a needle valve for controlling the supply of liquid fuel to the mixture nozzle and in the present instance this valve is connected to the lower end of the tubular plunger 19, so that as the said plunger moves in one direction or the other, the valve 28 is correspondingly shifted. Under normal conditions the valve 28 is open but is under the control of pressure conditions in the motor intake acting in opposition to a coiled spring 29 which bears against a fixed part of the stem 12 at one end and against the movable piston 30 at the opposite end. The piston 30 in the present instance is mounted for free sliding movement within the chamber 15. Thus the normal tendency of the spring 29 is to raise the piston 30, plunger 19 and valve 28 to maintain the fuel inlet fully open while a reduction in pressure beneath the plunger 30, or rather within the stem 12, below a definite pressure causes the spring to be overcome and the valve 28 to be partially closed. It will be noted that a port 31 is provided to form a communication between the interior of the stem 12 and the motor intake while a similar port 32 provides for the passage of air from the interior of the plunger 19 to the jet chamber 25. This port 32 is preferably below the normal liquid level or at least the level under starting and slow speed conditions so that the air drawn through is relatively saturated with liquid fuel.

Referring now to the main reservoir 4 for liquid fuel, 33 designates an air vent suitably formed in the casing 1 and communicating with the said reservoir above the normal liquid level whereby the liquid fuel is supplied by gravity action to the jet as will be understood. 34 designates an outlet leading from the storing reservoir 5 to the main reservoir 4 and having its mouth normally below the fuel level, so that the outlet is liquid sealed and the liquid from the storing reservoir 5 gradually replaces the liquid used from the main reservoir 4 through the action of the air bubbling or rising through the liquid sealed outlet 34.

35 designates the outlet from the auxiliary chamber 6 to the storing reservoir 5, this outlet, in the present instance, terminating well within the chamber 5 and having its mouth normally sealed by the stored liquid fuel. A valve 36 is arranged to control the opening and closing of the outlet 35 and for this purpose is provided with a reciprocable stem 37 which is connected to a lever 38 which carries a float 39 and has its fulcrum 40 intermediate the two points of connection, so that when the float rises the valve stem 37 is lowered and vice versa. The auxiliary chamber 6 is adapted to be subjected to the pressure conditions in the motor intake and to that end the casing wall is provided with an opening 41, the opening and closing of which is controlled by the movement of the stem 12, and as here shown the said stem is annularly grooved as shown at 42 to form a passage or connecting conduit with a port 43 which communicates by way of the channel 44 with the motor intake. Thus in one position of the throttle, the groove 42 will provide a full size communicating passage between the ports 41 and 43 and in another position of the throttle this communicating passage will be reduced in area to a proportionate extent both with the end in view of maintaining a substantially constant vacuum within the chamber 6.

In Figs. 4 to 8 inclusive, I have illustrated a modified form of the carbureter in which there in a plurality of liquid fuel chambers of the type shown in Fig. 2, one set of such chambers being arranged at one side of the carbureter and the other set at the opposite side and the construction affording means

to continuously supply liquid fuel to the jet nozzle while at the same time means are provided for replenishing an exhausted reservoir. The general operation of this multiple set type is to alternately provide a fuel feeding reservoir and a reserve fuel reservoir which comes into operation when the former is exhausted and during the time that the said exhausted chamber is automatically being replenished.

Referring to Figs. 5 and 8, 45 designates the carburetor casing which is longitudinally sub-divided by a partition 46 or the like into two auxiliary chambers 47 and 48 which have communication respectively by way of the outlets 49 and 50 with a main reservoir chamber 51 which supplies the fuel jet through the port 52. In view of the fact that the jet structure as well as certain of its adjuncts are similar in construction to the construction described in connection with Fig. 2, it is deemed unnecessary to here give a repetition of its details and therefore the essential parts necessary to an understanding of the operation of the modified form of the carburetor will be given in same reference numerals as applied to Fig. 2. In connection with the regulation of the vacuum conditions in the chambers 47 and 48, it will be noted that each is provided with a port 52 and 53, respectively, opening against the stem 12 of the throttle sleeve and so positioned as to align with a grooved and beveled notch 54 formed in the stem 12 so that one or the other of the said ports may be brought into communication with the port 55 leading to the channel 56 which has communication with the motor intake.

57 and 58 designate, respectively, float members located in the chambers 47 and 48 and respectively connected by the pivoted levers 59 and 60 and valve stems 61 and 62 with the valves 63 and 64 which control the outlets 49 and 50 from the respective auxiliary chambers 47 and 48. The valve stem 61 is provided with a shoulder part which serves as a support for a loosely mounted valve 65 which has sufficient clearance with respect to the lever 59 as to open the inlet channel 66 for the liquid fuel and which channel communicates with the low level liquid supply. A similar valve member 67 is carried by the stem 62 and operates in a similar manner to control the liquid fuel inlet for the chamber 48, as will be understood.

68 designates a lever pivotally mounted within the main reservoir 51 and having its ends respectively in contact with the valves 63 and 64 so that movement of either under actuation of the corresponding float will cause or permit the other valve to move in the opposite direction, thus making positive provision for closing one of the outlet valves 65 when conditions make it necessary for the

other to be open. The main fuel reservoir 51 is subject at all times to atmospheric pressure through the air vent 69 which is suitably formed in the casing and terminates above the normal liquid level in the said reservoir 51.

Referring now to the modification shown in Figs. 9 to 12 inclusive, the general construction of the carburetor is substantially the same as that heretofore described but the valve structure for controlling the feeding of fuel to the main reservoir is somewhat modified as well as the control of the communication of each auxiliary reservoir with the motor intake or suction producing means. In view of these changes or modifications, the reference characters will be applied as before to like parts described and those parts which are varied from the previous construction will be given new reference numerals.

Referring first to the means for subjecting the respective chambers 47 and 48 to the pressure conditions existing in the motor intake and the automatic control for this means, the description will be made with reference to but one of the chambers and its adjuncts, since the parts are identical in both and therefore the corresponding elements will be similarly numbered for convenience. 70 designates a conduit leading through a suitable web of the casing from the port 71 which opens against the stem 12 of the throttle structure and terminates at its opposite end in a two-way port 72, one branch of which leads to the chamber 47 and the other branch to the chamber 48. Each outlet branch from the port 72 is controlled by a loosely mounted valve 73 which extends through the wall of the casing and into the path of movement of the valve stem 61 which latter, as previously explained, is under the control of the float 57 and also carries the valve 63 which opens and closes the outlet to the reservoir 51. 74 designates a port for establishing communication between the main reservoir 51 and the atmosphere and the outlet of this port is preferably arranged in close proximity to the valve 63 and at substantially the normal liquid level in the reservoir 51 with the result that while the outlet 49 may be normally liquid sealed, any lowering of the level with the valve 63 open allows air to bubble through into the auxiliary chamber 120 and displace a certain amount of fuel which is used to replenish the main reservoir. The refilling of the auxiliary reservoir 47 is accomplished by providing a conduit 75 which in this instance is really a branch from the main liquid fuel conduit 76 which has communication with a low level liquid fuel supply. A check valve 77 is suitably mounted to control the outlet to the chamber 47 and since the valve 77 opens inwardly, I have

75

forced out of its position by the incoming path of its movement so that it may not be employed a suitable stop 78 located in the liquid fuel.

- 5 In connection with the control of the suction within the auxiliary chambers or receptacles 47 and 48, it will be noted that I have provided a circumferential groove 79 about the stem 12 which groove normally 10 permits a minimum passage or communication between each of the auxiliary receptacles and the motor intake and since the stem is also formed with a bevel notch 80, it will be evident that rotary movement of 15 the throttle valve stem will cause a variation in the volume of air or gas drawn through the aforesaid passage. The provision of the valves 73 for controlling the respective suction channels 72 secures, 20 through the coöperation of the floats, an alternate operation of the two auxiliary receptacles, that is, when one of the auxiliary receptacles is full and either feeding the main reservoir or being held in reserve, its 25 float will be in such a position that its valve 73 will practically cut off communication with the suction from the motor intake, while the opposite valve is open because the float level in the opposite chamber has been 30 lowered through use and consequently the suction or vacuum produced is utilized to draw in a new supply of liquid fuel by way of the valve 77. By reference to Fig. 11, it will be apparent that the two valves 35 63 and 64 are arranged as heretofore described to contact with the lever 68 for the purpose already explained.

The general operation of the several forms of my invention is the same, since 40 the complete unitary device acts as a means for feeding a gaseous mixture to a motor, controlling and proportioning the mixture in accordance with pressure variations in the motor intake and also providing a means 45 for continuously supplying liquid fuel in regulated quantities as required. Referring first to the throttle structure and its adjuncts, it will be noted that the throttle valve is substantially of hollow or tubular 50 construction at its central portion and within which the parts are so arranged and co-ordinated as to form not only the main fuel jet of the carburetor but also an auxiliary reservoir embodying air and fuel supply to 55 form an auxiliary jet which is particularly advantageous for starting or slow speed conditions. Assuming these latter conditions to exist and the throttle to be in its closed position, the fuel assumes a level in 60 the chamber 25 substantially co-incident with the two ports 21 and since at this time also but one of the outlets 22 is directly subject to the suction of the motor intake the other outlet 22 becomes an inlet for air from 65 the main air opening 8. Thus under a

starting condition air is drawn through the inlet 22 into contact with the liquid fuel and discharges through the outlet 22 to the motor intake while a second body of air is drawn through the ports 17, and passes 70 by way of the ports 32 beneath the level of the fluid and bubbles its way to the outlet 22 so that the resulting combined mixture is a saturated mixture well adapted for the requirements of starting or slow speed 75 work. Under running conditions of the motor, the throttle jet becomes less of an auxiliary or priming device since it is then transformed into the main fuel jet and with the throttle open, the suction is generally 80 sufficient to practically empty the chamber 25 of any surplus liquid fuel and the carbureting chamber draws directly upon the main fuel reservoir for its supply. In the present instance, I have provided an automatic regulation as an adjunct of the throttle valve and which operates to move the needle valve 28 in accordance with pressure conditions in the motor intake and the operation of this adjunct will be understood 85 by reference to the spring pressed plunger 19 which is normally held in such a position as to lift the valve 28 from its seat and provide a full opening for the liquid fuel. As suction develops in the motor intake under running conditions, the port 31 provides a communication by which the piston 30 is pulled in an opposite direction to the action of the spring and as the vacuum lowers below the adjustment of the 90 spring, the plunger 19 is moved to shift the valve 28 toward its seat and thus cut down the supply of liquid fuel. In this manner, the liquid fuel may be definitely proportioned to the air according to motor requirements and a substantially definite mixture 95 provided for running conditions whether under light load, heavy load, slow speed or high speed. It should also be noted that as the throttle valve is opened, the port 22, 100 which in closed position of the throttle is an air inlet, becomes an additional discharge outlet for the fuel, and these fuel outlets are arranged to discharge into the main carbureting chamber adjacent the central 105 portion thereof so that all of the fuel is picked up by the air out of contact with the walls of the chamber.

In connection with the automatic replenishing of the liquid fuel to the auxiliary receptacle or receptacles, it will be evident that running conditions of the motor produce considerable variation in the vacuum conditions and consequently were the auxiliary receptacle to be always subject to the same degree 110 of suction, there would be times when the suction would be insufficient to draw a new supply of liquid fuel from the low level source and at other times the suction might readily be sufficient to cause flooding or 115

overflowing of the auxiliary receptacle. To overcome disadvantages of this character, I have here provided a means for automatically producing substantially a constant vacuum in the auxiliary receptacle or receptacles and in this instance have utilized, as one way of accomplishing the end, the throttle valve or its adjuncts to give the desired results. Thus the grooved stem of the 10 throttle valve forms a communication between the port of the auxiliary receptacle and the port of the chamber to the motor intake, and this communication, in one position of the throttle, gives a minimum degree 15 of suction, and in another position of the throttle, a maximum degree of suction, so that when the suction is low, that is, within an ounce or so of atmospheric pressure, the opening to the auxiliary receptacle will be 20 at maximum, while when the suction is high, the opening is correspondingly reduced to a minimum.

It will now be apparent that I have devised a novel and useful construction which 25 embodies the features of advantage enumerated as desirable in the statement of the invention and the above description and while I have in the present instance shown and described the preferred embodiment thereof 30 which has been found in practice to give satisfactory and reliable results, it is to be understood that the same is susceptible of modification in various particulars without departing from the spirit or scope of the invention read in the light of the foregoing 35 specification and the following claims and without sacrificing any of its advantages.

What I claim is:

1. In a carbureter, a casing forming a 40 main fuel reservoir, a carbureting chamber and an auxiliary receptacle for liquid fuel, said receptacle having communication with a low level liquid fuel supply, a conduit forming a communication between said receptacle and the motor intake, manually operable means to vary the size of said conduit to produce a substantially constant 45 vacuum in said receptacle and means to intermittently admit air from said main fuel reservoir to said receptacle to break said 50 vacuum and replenish said fuel reservoir.

2. In a carbureter, a casing forming a main fuel reservoir, a carbureting chamber and a plurality of auxiliary receptacles for 55 liquid fuel, said receptacles each having communication with a low level liquid fuel supply, means to automatically replenish the

fuel reservoir from one or the other of said receptacles and means common to both receptacles for maintaining a substantially constant vacuum in one or the other of said receptacles.

3. In a carbureter, a casing forming a main fuel reservoir, a carbureting chamber 60 and a plurality of auxiliary receptacles for liquid fuel, said receptacles each having communication with a low level liquid fuel supply, means to automatically replenish the fuel reservoir from one or the other of said receptacles, a conduit forming a common 65 means of communication between said receptacles and the motor intake and manually operable means to vary the opening of said conduit, whereby the vacuum in one or the other of said receptacles remains substantially constant irrespective of pressure conditions in the motor intake during the operation of the motor.

4. In a carbureter, a casing forming a main fuel reservoir, a carbureting chamber 70 and a plurality of auxiliary receptacles for liquid fuel, said receptacles each having communication with a low level liquid fuel supply, means to automatically replenish the fuel reservoir from one or the other of said 75 receptacles, a conduit forming a communication between said receptacles and the motor intake, a throttle valve and means under the control of said throttle valve to vary the opening of said conduit according to requirements.

5. In a carbureter, a casing forming a main fuel reservoir and an auxiliary supply receptacle, said receptacle having an air vent sealed and unsealed by the liquid fuel in 80 said main reservoir, a throttle valve and means controlled by said throttle for creating and regulating a vacuum in said receptacle.

6. In a carbureter, a casing forming a 85 main fuel reservoir and an auxiliary supply receptacle connected to a main low level liquid fuel source and provided with an air vent sealed and unsealed by the liquid fuel in 90 said main reservoir, means forming a constant communication between said receptacle and the motor intake, a throttle valve and means for varying the size of said communication in accordance with the position of 95 said throttle valve.

In testimony whereof, I have hereunto signed my name.

ALFRED WEILAND.
